UNITED STATES PATENT OFFICE.

CHARLES H. BAYLEY, OF BOSTON, MASSACHUSETTS.

SKIVING-MACHINE.

SPECIFICATION forming part of Letters Patent No. 632,984, dated September 12, 1899.

Application filed December 27, 1898. Serial No. 700,313. (No model.)

To all whom it may concern:

Be it known that I, CHARLES H. BAYLEY, of Boston, in the county of Suffolk and State of Massachusetts, have invented certain new and useful Improvements in Skiving-Machines, of which the following is a description sufficiently full, clear, and exact to enable those skilled in the art to which it appertains or with which it is most nearly connected to 5 make and use the same.

My invention has relation to skiving-machines, and particularly to that class of skiving-machines of which the machine disclosed in an application filed by me August 16, 1898, bearing Serial No. 688,701, is a type, and is intended to so improve the construction of that class of machines as to permit the use of a bearing-sleeve for the knife-shaft and yet avoid all objections that have heretofore been urged by practical operators against the use of a bearing-sleeve.

To these ends my invention consists of certain features of construction by which is secured a quick and absolutely accurate adjustment of the knife relative to the feed-roll, simple and perfect provision being made throughout for compensating for wear of engaging parts and by which also the quick and easy removal of the sleeve containing the 25 knife-shaft is permitted without in the least interfering with the adjusting device and the sleeve or without interfering with the adjustment or relationship of the sleeve with respect to the knife-shaft or without in any 30 other way disconnecting or dismantling the parts of the machine.

In the accompanying drawings I have illustrated one of the modes in which I have contemplated embodying my aforesaid improvements.

Figure 1 is a front elevation of a skiving-machine, the feed-disk being removed to more clearly show the parts affected by my invention. Fig. 2 is a detail end elevation showing the grinder and the knife in proper relationship to each other and illustrating clearly the means for adjusting the sleeve and compensating for wear. Fig. 3 is a detail view in vertical section illustrating the adjustable 45 engagement between the sleeve and the knife-shaft. Fig. 4 is a plan view, partly in section, of the sleeve, knife-shaft, and adjusting

device. Fig. 5 is a sectional plan view on line $x-x$ of Fig. 2. Fig. 6 is a plan view of that portion of the bracket that supports the 55 bearing-sleeve.

I will now give a detailed description of the form of my invention illustrated in the drawings; but since some of the features disclosed are made the subject of the application above 60 referred to I shall refer to them only so far as may be necessary and proper to give an accurate understanding of the invention herein claimed.

a designates the main driving-shaft, from 65 which motion is communicated to the feed-roll b , to the knife-shaft c , and to the grinder d in any suitable manner, as will be understood by those skilled in the art.

The knife-shaft c is mounted in a supporting or bearing sleeve e . Said bearing-sleeve is mounted in a movable bracket f , which may have such adjustments as may be proper and suitable to secure the proper relationship between the knife and the feed-roll. Upon 70 this bracket f I have shown, as in my former application, an additional bracket f' , secured thereto and supporting the grinder d , so that the grinder d and the knife may be simultaneously inclined or tipped by means of the 75 adjusting-screw f^2 , as pointed out in my former application and as will be readily understood by those skilled in the art. By means of the straps or clamping members g , which are tightened to place by means of the screws 80 h , the sleeve e is held in said bracket in such a way as to permit it to slide longitudinally in said bracket while making it possible to 85 quickly and easily remove said sleeve by withdrawing said screws. I form intermediate 90 of the ends of said sleeve, so as not to interfere with the vertical adjustment, a lug or shoulder i , which is recessed to permit the insertion of a collar j , which is adjustably secured to the shaft c by means of a set-screw 95 or the like. The lower end of the knife-shaft is formed with a hub l , which abuts against the lower end of the sleeve and which by bearing against the lower end of said sleeve 100 prevents the upward movement of the shaft in the sleeve. The collar j , secured to the shaft, engages with the interior face of the recessed lug or shoulder, so as to prevent longitudinal movement of the shaft in the

sleeve. It is obvious that as fast as these bearing-surfaces become worn the set-screw holding the collar may be loosened to permit the knife-shaft to be thrust upward until it 5 bears firmly against the lower end of the sleeve and that while the knife-shaft is held in that position the adjustable collar can be pressed firmly to its seat and again secured to the shaft while held in that position, thus 10 securing perfect freedom from longitudinal play by simply loosening or tightening a single set-screw. The lug or shoulder i is extended some little distance to the rear of the sleeve and is slotted in order to form a pair 15 of jaws i' , which are adjustable toward or away from each other by means of a screw i^2 , the purpose of which will presently be described. An adjusting-screw m is mounted in the bracket f to the rear of the sleeve and is provided 20 with a collar or shoulder m' . This collar forms an open engagement with the recess between the jaws i' . It is obvious that as the collar m' and the opposite bearing-faces of the jaws i' become worn the screw i^2 may be 25 tightened, thus drawing two jaws together and compensating for the wear of the engaging parts. I also provide suitable means, such as a binding-screw n , for clamping the adjusting-screw m against accidental movement, which may be caused by the constant 30 jarring of the machinery. It will thus be seen that the parts of the mechanism under consideration are so constructed as to absolutely prevent backlash at every point as fast 35 as the parts become worn. Not only is the engagement between the sleeve-adjusting device and the sleeve adjustable to compensate for wear, but is so constructed as not to interfere in the least with the instantaneous 40 withdrawal of the sleeve from its supporting-bracket, so that by the mere removal of the screws h the sleeve and knife-shaft may be withdrawn without making it necessary to loosen other connections or in any way to dismantle the machine.

It will be obvious to the skilled artisan that by my invention I have completely overcome the objections that have heretofore been made to the use of a bearing-sleeve for the rotary 50 knife-shaft, as I secure absolute freedom from backlash or play of the parts and also secure a construction which permits the prompt and easy removal of the sleeve without interfering with the adjusting mechanism or in any 55 other way dismantling the machine.

Having thus explained the nature of the invention and described a way of constructing and using the same, though without attempting to set forth all of the forms in which it 60 may be made or all of the modes of its use, it is declared that what is claimed is—

1. In a skiving-machine, the combination with a rotary knife-shaft, of a sleeve surrounding and supporting said shaft, a movable bracket, means for detachably holding said sleeve in said movable bracket, whereby the sleeve may be quickly and easily withdrawn

to permit the removal of the knife without disturbing the relationship of the sleeve to the shaft. 70

2. In a skiving-machine, the combination of a rotary knife-shaft, a longitudinally-adjustable supporting-sleeve surrounding said shaft, an adjusting device having engagement with said sleeve, said engagement being itself 75 adjustable to compensate for wear, whereby any longitudinal play of the sleeve is prevented.

3. In a skiving-machine, the combination of a rotary knife-shaft, a supporting-sleeve 80 surrounding the same, said sleeve being recessed intermediate of its ends to receive a collar, said collar being adjustably secured to said shaft, so as to permit free rotation of the collar and the shaft, while preventing 85 longitudinal play in the sleeve.

4. In a skiving-machine, the combination of a rotary knife-shaft, a bearing-sleeve surrounding the same, a lug or shoulder formed on said sleeve intermediate of its ends, said 90 shoulder being recessed to receive an adjustable collar secured to the shaft, and an adjusting device having engagement with the lug or shoulder to secure longitudinal adjustment of the sleeve and knife-shaft. 95

5. In a skiving-machine, the combination of a rotary knife-shaft, a bearing-sleeve, surrounding the same, said bearing-sleeve being detachably mounted in a movable bracket, a lug projecting from said sleeve and an adjusting device arranged to engage with said lug without interfering with the removal of the sleeve. 100

6. In a skiving-machine, the combination of a rotary knife-shaft, a bearing-sleeve therefor, a supporting-bracket for said bearing-sleeve, a lug projecting from said sleeve, an adjusting-screw having detachable engagement with said lug, substantially as described. 105

7. A device for securing vertical adjustment of the knife and its shaft relative to the feed-roll, comprising a bearing-sleeve, a lug thereon, said lug being slotted to form clamping-jaws, an adjusting-screw having a collar 115 arranged to pass between said jaws, and means for drawing said jaws together to form a close engagement with the collar, substantially as described.

8. In a skiving-machine, the combination 120 of a rotary knife-shaft, a bearing-sleeve therefor, said bearing-sleeve being mounted to slide longitudinally in a supporting-bracket, an adjusting device for controlling said sliding movement, and means for positively fastening the device against accidental movement while the machine is in operation. 125

9. In a skiving-machine, the combination of an adjustable bracket, means for securing a positive and accurate adjustment thereof, 130 a rotary knife-shaft and a co-operating grinder carried by said bracket, said knife-shaft being surrounded and supported by a sliding detachable sleeve, substantially as described.

10. In a skiving-machine, the combination of a rotary knife-shaft, a bearing-sleeve therefor, said bearing-sleeve being mounted to slide longitudinally in a supporting-bracket, 5 an adjusting device for controlling said sliding movement, the engagement between said adjusting device and said sleeve being detachable to permit the quick and easy removal of the knife-shaft with its sleeve.

In testimony whereof I have signed my name to this specification, in the presence of two subscribing witnesses, this 21st day of December, A. D. 1898.

CHARLES H. BAYLEY.
